UNITED STATES PATENT OFFICE

2,575,161

RESILIENT ELECTRIC SOCKET CONTACT ELEMENT

Stanley Thomas Deakin, Ewell, England, assignor to British Mechanical Productions Limited, London, England, a British Company

Application February 17, 1948, Serial No. 8,858
In Great Britain May 31, 1946

Section 1, Public Law 690, August 8, 1946
Patent expires May 31, 1966

6 Claims. (Cl. 173—328)

1

This invention relates to electric resilient socket contact elements for the reception of the pins of a plug member or a valve, or of switch elements, the tongues of a fuse holder or like round or flat equivalent plug members.

The invention provides a socket contact element for the above purpose comprising two substantially parallel contact faces between which the plug member is received and which are integral with or attached to the ends of a zig-zag or S-shaped portion connecting the contact faces together and lying in a plane perpendicular to the direction of insertion and withdrawal of the plug member.

It is an advantage of the construction of a contact element according to the invention that it allows for a substantial amount of resilient movement of the contact faces and a further advantage is that substantially equal contact pressure is applied to the plug member across the width of the contact faces (i. e., transverse to the direction of movement of the plug member) even though the plug member may taper in thickness across its width.

In a preferred construction according to the invention the contact element is fabricated from a blank cut from sheet metal and the contact faces are provided by tongues extending edgewise from the ends of the resilient portion.

One specific form of socket contact element according to the invention and a modification thereof in conjunction with a valve holder will now be described by way of example and with reference to the accompanying drawings, in which—

Figure 1 shows a sheet metal blank from which the socket element is fabricated;

Figure 2 is a plan view of the completed element;

Figure 3 is a front end view of the element;

Figure 4 is a rear end view of the element, and

Figure 5 is an elevation of the element;

Figure 6 is a view corresponding to Figure 2 showing the modification;

Figure 7 is a view corresponding to Figure 5, of the modification;

Figure 8 is a section on the line 8—8 in Figure 7;

Figure 9 is a view of the top of a valve holder;

Figure 10 is a view to an enlarged scale of part of the underside of the holder shown in Figure 9;

Figure 11 is a view similar to Figure 10 but showing the lugs on a contact element passing through the slot in the holder;

2

Figure 12 is a section through the holder, and Figure 13 is a section through a modified form of holder.

The blank shown in Figure 1 is cut to provide a shank 1, a cross-piece 2 and two tongues 3. To form the contact element the cross-piece 2 is bent to approximately S-shape as shown in Figures 3 and 4 and the two tongues 3 are bent as shown in Figure 2 to provide contact faces 4. The shank portion 1 provides a tag for the attachment of the lead wire.

In use, the plug pin 5, which may be round or flat, is inserted end-wise between the contact faces 4 as indicated in dotted lines in Figure 2. The pressure of the contact faces is provided in part by the resilience of the tongues 3, but to a larger extent by the resilience of the S-shaped portion 2. It will be observed that the free ends of the S-shaped portion, which have the maximum freedom of movement, are in opposed relationship, with the result that substantially constant contact pressure is applied across the width of the contact faces.

In the modified form of the contact element 25 shown in Figures 6 to 8 there are added to the shank portion of the element two short lateral lugs 10 spaced away from the part 2 of the element and curved, in end view of the element, to conform with the S-shape of the part 2.

The holder shown in Figures 9 and 12 is intended for the reception of the pins of an eight-pin valve and has eight contact elements, as just described, located in a corresponding number of recesses 11 in the holder. Each recess is of rectangular form closely embracing the contact faces and S-shaped portion of the element while allowing resilient outward movement of the contact faces. Leading from each recess through the base of the holder there is a slot 12 of width

less than the recess and less than the width of the element between the tips of the lugs when the shank is as shown in Figure 10, parallel with the sides of the slot. The slot, however, is sufficiently wide to pass the lugs when the shank is twisted to a diagonal position as shown in Figure 11. The contact elements are assembled in the holder in the manner described above and are retained in position by the lugs 10 abutting against the outer face 13 of the base of the holder

50 at the sides of the slots and by the S-shaped portions abutting against the shoulders 14 at the bottoms of the recesses as shown in Figure 12. The modified holder shown in Figure 13 comprises a moulded body portion 21 and a retaining plate 22 of reinforced synthetic resin sheet. The body portion is of cylindrical form and has a

55

number of recesses 23 extending in the axial direction and corresponding in number and spacing to the pins of the valve with which the holder is to be used. In each recess 23 there is a contact element 24 as described above. The contact faces 4 on the elements 24 are positioned near the bottom of the recesses 23 and each recess has a through passageway 25 at its bottom for the corresponding valve-pin. The contact elements 24 are held in position by the retaining plate 22 which has apertures passing over the tags 10 of the contact elements and the plate engages the adjacent sides of the S-shaped portions 2 of the elements to hold them in the recesses in the body portion. The retaining plate 22 is held in position against the rear end face of the body portion by a central tubular rivet 26.

The invention is not restricted to the precise constructional details described above and shown in the drawings. For example, changes may be made in the shape of the S-shaped portion 2. If it is desired to increase the stiffness of the element the radius of curvature of the bends of this portion may be reduced so that it becomes of zig-zag shape and if on the other hand it is desired to decrease the stiffness of the element the radius of curvature may be increased.

I claim:

1. A resilient socket contact element for the purpose specified comprising a length of resilient strip material reversely bent about lines transverse to the length of the material into the form of a zigzag having substantially parallel legs and also comprising two opposed contact faces provided by two tongues extending laterally from the edges of the end legs of the zigzag strip material on one side thereof and spaced apart for the reception between them of a plug member, the zigzag providing a resilient support for the tongues to afford contact pressure on the plug member.

2. A resilient socket contact element for the purpose specified comprising a length of resilient strip material reversely bent about lines transverse to the length of the material into a zigzag having an odd number of substantially parallel legs, two opposed contact faces provided by two tongues extending laterally of the strip from the edges of the end legs of the zigzag on one side thereof and spaced apart for the reception between them of a plug member, the zigzag providing a resilient support for the tongues to afford contact pressure on the plug member, a shank portion extending from the center leg of the zigzag on the opposite side thereof and, on the shank, laterally extending lugs spaced from the zigzag.

3. A resilient socket contact element for the purpose specified comprising a length of resilient strip material reversely bent about parallel lines transverse to the length of the material into a zigzag having an odd number of substantially parallel legs, two opposed contact faces provided by two tongues extending laterally from the edges of the end legs of the zigzag on one side thereof and spaced apart for the reception between them of a plug member, the zigzag providing a resilient support for the tongues to afford contact therefrom on the plug member, a shank extending from the center leg of the zigzag on the opposite side thereof and, on opposite sides of the shank two laterally extending lugs spaced from the zigzag and oppositely bent in directions to conform to the zigzag.

4. A socket member for an electrical plug and

socket connection which socket member comprises at least one resilient socket contact element comprising a length of resilient strip material reversely bent about lines transverse to the length of the material into a form of a zigzag having an odd number of substantially parallel legs, two opposed contact faces provided by two tongues extending laterally from the edges of the end legs of the zigzag on one side thereof and spaced part for the reception between them of a plug member, the zigzag providing a resilient support for the tongues to afford contact pressure on the plug member, a shank portion extending from the center leg of the zigzag on the opposite side thereof and, on the shank, laterally extending lugs spaced from the zigzag, and a socket holder having a slot through which the shank passes, the element being held in position in the holder by engagement with one side of the holder of the said zigzag and by engagement with the other side of the holder of the said lugs.

5. A socket member for an electrical plug and socket connection which socket member comprises at least one resilient socket contact element comprising a length of strip material reversely bent about lines transverse to the length of the material into the form of a zigzag having an odd number of substantially parallel legs, two opposed contact faces provided by two tongues extending laterally from the edges of the end portions of the strip material on one side thereof and spaced apart for the reception between them of a plug member, the zigzag providing a resilient support for the tongues to afford contact pressure on the plug member, a shank extending from the center leg of the zigzag on the opposite side thereof and, on the shank, laterally extending lugs spaced from the zigzag, and a socket holder having a recess therein within which the aforesaid zigzag is received and closely embraced, a slot in the base of the recess through which the shank extends outwardly of the holder which slot is of reduced dimensions in relation to the recess thereby providing a shoulder at the bottom of the recess, and in which socket the socket contact element is retained in position by embracing the holder between the zigzag abutting against the shoulder on one side and the aforesaid lugs abutting against the external face of the holder on the other side.

6. A socket member, for an electrical plug and socket connection, as claimed in claim 5 in which the slot has a dimension between its opposed side faces slightly greater than the thickness of the shank and the lugs, and in which the lugs are oppositely bent in directions to conform with the zigzag and abut against the base at the sides of the slot.
